CLAIM

The ornamental design for a tubular connector as shown and described.

DESCRIPTION

FIG. 1 is a perspective view of the tubular connector according to the new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The ornamental design which is claimed is shown in solid lines in the drawings. The evenly spaced broken lines depict portions of the connector that form no part of the claimed design. The dot dash dot broken lines denote the boundaries of the claimed area and form no part of the claim.
